UNITED STATES PATENT OFFICE.

MAY F. LANIER, OF GREENWICH, CONNECTICUT, ASSIGNOR TO CAMP FIRE GIRLS, AN ASSOCIATION INCORPORATED IN THE DISTRICT OF COLUMBIA.

DESIGN FOR A CEREMONIAL GOWN.

45,010.

Specification for Design.

Patented Dec. 9, 1913.

Application filed October 9, 1913. Serial No. 794,346. Term of patent 3½ years.

To all whom it may concern:

Be it known that I, MAY F. LANIER, a citizen of the United States, and a resident of the city of Greenwich, county of Fairfield, and State of Connecticut, (whose post-office address is "Rock Ridge," in said city,) have invented a new, original, and ornamental Design for Ceremonial Gowns, of which the following is a specification, reference being had to the accompanying drawing, forming part hereof, in which—

I claim:

The ornamental design for a ceremonial gown as shown.

MAY F. LANIER.
